DESIGN FOR AN INDUSTRIAL TRUCK

Elmer J. Dunham, Battle Creek, Mich., assignor to
Clark Equipment Company, Buchanan, Mich.,
a corporation of Michigan

Application September 24, 1938, Serial No. 80,075

Term of patent 14 years

To all whom it may concern:

Be it known that I, Elmer J. Dunham, citizen of the United States, residing at Battle Creek, in the county of Calhoun and State of Michigan, have invented a certain new, original, and ornamental Design for Industrial Truck, of which the following is a specification, reference being had to the accompanying drawing, forming a part thereof.

In the drawing:

Figure 1 is a rear quarter perspective view of a truck embodying my new design;

Figure 2 is a front quarter perspective view of the truck shown in Figure 1;

The side of the device opposite that shown in the drawing is substantially the same with the exception of the battery casing shown on the right hand side of the steering column, the device being substantially symmetrical with respect to a longitudinal mid-plane.

I claim:

The ornamental design for an industrial truck, as shown and described.

ELMER J. DUNHAM.
